CLAIM

The ornamental design for a drawer side panel, as shown and described.

DESCRIPTION

FIG. 1 is a perspective view of a drawer side panel, showing our new design according to a first embodiment;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 is an enlarged fragmentary view of left side of the perspective view of FIG. 1;

FIG. 9 is an enlarged detailed view of the encircled area 9 in FIG. 8;

FIG. 10 is a perspective view of a drawer side panel, showing our new design according to a second embodiment;

FIG. 11 is a front view thereof;

FIG. 12 is a rear view thereof;

FIG. 13 is a left view thereof;

FIG. 14 is a right view thereof;

FIG. 15 is a top plan view thereof;

FIG. 16 is a bottom plan view thereof;

(Continued)

FIG. 17 is an enlarged fragmentary view of left side of the perspective view of FIG. 10; and,
FIG. 18 is an enlarged detailed view of the encircled area 18
in FIG. 17.
